DRIVING CONTROL MEANS FOR
AUTOMOBILESFredrick H. Jordan, Chicago, Ill., assignor to
Bendix Products Corporation, South Bend, Ind.,
a corporation of Indiana

Application February 9, 1931, Serial No. 514,448

5 Claims. (Cl. 192—.01)

This invention relates to driving control means for automobiles, and it has for its principal object to simplify the mechanism and minimize the manual and pedal operations on the part of the driver by providing more particularly for an automatic actuation of the usual clutch device which is now generally provided for alternately connecting and disconnecting the engine shaft and the propeller shaft in the ordinary present day automobile structures.

Other particular objects and advantages to be attained will hereinafter more fully appear.

The invention consists in the novel application of the controlling mechanism to the automobile, and in the parts, and combinations and arrangement of parts, as hereinafter described and pointed out with particularity in the appended claims.

Referring now to the drawings illustrating a practical adaptation of the invention,—

Fig. 1 is a view, somewhat schematic, illustrating fragmentarily the parts of an automobile engine and the controlling mechanism directly associated with the present invention;

Fig. 2 is a view, on an enlarged scale, partly in elevation and partly in section, illustrating details of the clutch controlling valve;

Fig. 3 illustrates the same valve as viewed at right angles to the position shown in Fig. 2;

Fig. 4 is a cross-section through the valve showing the relative location of the ports thereof when the valve is set to create the vacuum in the clutch releasing cylinder; and

Fig. 5 is a similar view illustrating the cooperative relation of the ports when the valve is set to admit air into the clutch releasing cylinder.

Referring now to the drawings, numeral 10 designates the intake manifold of an automobile engine, through which the fuel charges are supplied to the respective power cylinders of the engine in the usual manner. Connected to the manifold 10, by the pipe 11, is the carburetor 12 which may be of any suitable construction and arrangement, and for the purposes of illustration is merely shown conventionally in the drawings. The throttle valve of the carburetor (not shown), is provided externally of the casing or shell of the carburetor with an oscillatory actuating arm 13, said arm being pivotally connected, as at 14, to a rod 15 which, as conventionally illustrated, is slidably supported in a guide member or bracket 16 with slight play in the bearing so that the rod is permitted limited oscillatory motion during its longitudinal reciprocation in 55 order to compensate for the arcuate travel at the

point of pivotal connection between the rod and the arm 13 which actuates the throttle valve of the carburetor. The rod 15 is pivotally connected, as at 17, to a link 18, which is in turn pivotally attached, as at 19, to an arm 20 of a pedal or treadle member 21, the latter being pivotally supported, as at 22, on the foot-board 23 of the automobile body within convenient reach for the application of the driver's foot. The link 18, as shown, is also pivotally supported by a supplemental oscillatory arm 24, said arm being pivotally attached at one end, at the point of pivotal connection 19, between the link 18 and arm 20 of the pedal or treadle 21, and pivotally supported at its opposite end, as at 25, on the underside 15 of the footboard 23. A spring 26, which is connected at one end to the link 18, as at 27, and at its opposite end to the underside of the foot-board 23, as at 28, yieldably holds the rod 15 and the connected throttle valve arm 13 in normally 20 retracted position. By this arrangement, which, as hereinbefore noted, is merely conventionally shown, but illustrates in a general way the usual manner of operating the carburetor throttle valve, the valve is opened upon the depression of 25 the pedal or treadle member 21 under the pressure of the driver's foot.

According to the usual method of driving an automobile, the foot pedal or treadle 21, or an equivalent device, is utilized during the process 30 of operating the engine, for acceleration of power after the car has been started through the instrumentality of the hand operated lever which is usually provided on the steering column or otherwise in convenient reach of the driver's hand. 35 Usually, the operable connection between the hand lever (not shown) is effected through the medium of a rod 29 on which the hand lever is mounted, said rod extending axially through the steering column 30 and being projected beyond 40 the lower end of the latter as at 31, where it is provided with a segmental gear 32 which cooperatively engages a similar gear 33 fixed on an angularly disposed stub shaft 34, the latter having an arm 35 fixed thereon. The arm 35, which, of course, oscillates about the axis of the stub shaft 34, is pivotally attached as at 36 to one end of a rod 37, the opposite end of said rod being pivotally attached, as at 38, to a crank arm 39, which is connected by the shaft 40 to a second 50 arm 41, the latter being connected, as at 42, preferably by a suitable universal joint, to the end of a rod 43, whose opposite end is swiveled, as at 44, to a sleeve 45 which is slidably mounted 55 on the rod 15, said sleeve, when moved in one

direction, engaging a collar 46 fixed on the rod 15. By this construction, the rod 15 is moved by the manipulation of the hand lever, through the intermediary of the several connections between the shaft 29 and sleeve 45 just above described, so as to open the carbureter throttle valve. In this actuation, of course, the foot pedal or treadle member 21 moves with the rod 15 owing to the link connection between the parts as hereinbefore described. However, the foot pedal or treadle member 21 may be depressed to actuate the rod 15 without disturbing the hand throttle actuating lever either in its normally closed position or in the position to which it has been adjusted.

The mechanism, as thus far described, is illustrative of that by which the throttle valve is controlled in the ordinary automobile equipment. In the utilization of this mechanism the hand throttle lever is usually manipulated to open the carbureter throttle valve, slightly at first, in starting the engine, and gradually opening the throttle valve further after the engine is warmed up and the car is about to be propelled. After the car is underway and it is desired to accelerate the speed thereof, the hand throttle lever is usually left in the adjustment where it was set for a certain predetermined speed, and the pedal or treadle member 21, which is commonly termed the "accelerator", is pressed by the driver's foot, thereby opening the carbureter throttle valve to a greater degree and accordingly increasing the fuel charge which is taken into the power cylinders of the engine through the manifold 10. Inasmuch as the driver's left foot is necessarily kept free for application to the pedal of the clutch lever in an emergency, the right foot is alternately used for manipulating the brake pedal and the accelerator, requiring considerable thought and care on the part of the driver to avoid making the mistake of applying the foot to the wrong pedal, as well as tiring the driver when in congested traffic, due to the necessarily frequent manipulation of the clutch pedal, which latter is moved against the strong spring tension obviously provided in the mechanism for keeping the clutch normally engaged.

In accordance with the present invention, which has been brought about primarily to automatically effect the depression of the clutch pedal lever and consequent disengagement of the clutch between the engine crank shaft and the propeller shaft of the driving mechanism, under certain conditions, a device that is actuated by the suction in the fuel supply pipe connections and manifold between the carbureter and engine, during the operation of the engine, is provided, preferably in the form of a cylinder 47 in which reciprocates a piston 48 having one end of a connecting rod 49 pivoted thereto as at 50, the opposite end of the rod being pivotally attached, as at 51, to the clutch lever 52. The clutch lever is of the ordinary form and arrangement, and it is provided at its end with a pedal extension 53 which is projected through the usual slot 54 provided therefor in the footboard 23 of the automobile body in convenient reach of the operator's left foot, his right foot being used alternately in the manipulation of the regular brake pedal and the accelerator pedal 21. In the drawings the brake pedal, which is usually located adjacent the accelerator pedal, is omitted and the clutch lever 52 is merely shown conventionally, its pivotal point being indicated at 55, and the spring which yieldably holds the clutch lever and the connected clutch device (not shown) in normal

engaging position being also conventionally shown at 56.

For the purpose of more clearly illustrating the present invention, the clutch lever 52 is shown in its normal raised or engaging position in dotted lines, and in depressed or clutch disengaging position in full lines. In practice, the cylinder 47, which is merely shown conventionally in the drawings, is obviously mounted on some conveniently located portion of the engine frame 10 or housing, or on the chassis frame.

The cylinder 47 is provided with a port 57 which communicates with the space between its closed end and the piston 48, said port being connected by a pipe 58 to a controlling valve 59, the details of which will be presently described, said controlling valve being in turn connected by a pipe 60 to the fuel pipe connection 11 between the intake manifold of the engine and the carbureter 12. The interior diameter of the cylinder 47, and the area of the working face of the piston 48, are such that when a vacuum is created in the space in the cylinder between its closed end and said piston 48, the piston is thereby drawn toward said closed end of the cylinder and, consequently, with power sufficient to retract the clutch lever 52 against the tension of the spring 56.

Preferably, the controlling valve 59 comprises a cylindrical body portion 61 which is open at both ends and externally screw-threaded for the reception of cap members or heads. As shown, the cap member or head 62 at one end of the cylinder 61, is provided with an externally screw-threaded axial nipple 63 for the attachment of a coupling element 64 by which the connection with the pipe 58 is effected. The cylinder 61 is further provided with an integral lateral nipple extension 65 for the reception of a coupling element or union 66, by which the connection with the pipe 60 is effected. At the opposite end of the cylindrical portion 61 is a cap member or head 67 provided with an axial opening 68.

Fitted rotatably in the cylindrical portion 61 of the controlling valve 59 is a hollow cylindrical valve member 69 which is open at one end so as to be in constant communication with the pipe 58 through the nipple 63 and coupling member 64, the opposite end of the member 69 being closed, as at 70, and provided with an axial stem or spindle extension 71, the outer end portion of which is screw-threaded, as at 72, for the reception of a jam nut 73, which latter is provided for the purpose of releasably securing, in adjusted position, the stem portion 74 of a lever member 75 which is inserted through a transverse opening provided therefor in the axial stem or spindle extension 71 of the valve member 69. Sleeved on the stem or spindle portion 71 is a washer 76 which abuts the stem portion 74 of the lever member 75, while another washer 77 is located on said stem or spindle portion adjacent to the head 67, said washer 77 being preferably provided with a central embossment affording a gland for the reception of an interposed packing ring or gasket 78 for preventing leakage through the opening 68 in the cap member or head 67. Interposed between the two washers 76 and 77 and coiled about the stem or spindle extension 71 of the valve member 69, is a spring 79, which is constantly under tension and of strength sufficient to hold the closed end portion of the member 69 in contact with the inner face of the cap member or head 67 and at the same time exert compressive pressure upon 75

the packing ring or gasket 78, thereby creating sufficient frictional resistance preventing a too free movement of the valve member 69 and at the same time not unduly resisting its rotation in the regular course of operation.

The valve member 69 is provided with a port 80 which, as shown more clearly in Figs. 2 and 4 of the drawings, is normally in communicable registration with the nipple extension 65 of the body portion 61 of the valve, in which relation of said port 80 and nipple extension 65 communication is established between the intake manifold connection 11 of the engine and the clutch releasing cylinder 47. If the engine is operating during this relation of the port 80 and nipple extension 65 the suction creates a vacuum in the cylinder 47, thereby drawing the piston 48 towards the closed end of the cylinder and, of course, the clutch lever 52 is moved about its pivotal axis 55, owing to the connection 49 between it and said piston 48. However, if the valve member 69 is rotated to bring the port 80 into communication with a port 81 provided in the body portion 61 of the controlling valve 59, adjacent to the nipple extension 65, as illustrated in Fig. 5 of the drawings, communication with the intake manifold connection 11 of the engine is cut off and atmospheric pressure is restored in the cylinder 47 through the communicating ports 80 and 81 and pipe 58, whereupon the spring 56 returns the clutch lever to normal position and effects the driving connection between the crank shaft of the engine and the propeller shaft of the car.

The actuation of the valve member 69 is effected by a reciprocating and pivotal link connection between the lever member 75 and the carburetor throttle valve operating rod 15. To this end, the lever member 75 is formed with an angular extension 82 which is provided with a longitudinal slot 83. In this slot 83 a stud 84 is pivotally and slidably mounted, said stud being provided with a head 85 at one side of the lever extension 82 and a collar 86 on the opposite side thereof, washers 87 and 88 being respectively interposed between said head portion and collar 86 and the adjacent sides of the lever extension 82, and the stud being retained in place by a cotter pin 89. The head portion 85 of the stud is provided with a screw-threaded transverse opening for the reception of the screw-threaded end portion 90 of a rod 91, said rod being secured in longitudinally adjusted relation to the head 85 by a jam nut 92. The opposite end of the rod 91 is pivotally attached, as at 93, to an arm 94 which is sleeved slidably on the rod 15, as at 95, between a spaced pair of collars 96 and 97 fixed to the rod 15. Normally, in the closed position of the carburetor throttle valve and the communicable relation between the port 80 and nipple extension 65 of the controlling valve 59, the portion 95 of the arm 94 is in engagement with the collar 96 on the rod 15, at which time, also, the accelerator pedal 21 is in its normal raised position and the rod 43 and other connections between the rod 15 and the hand throttle controlling lever are in their normal condition. The normal positions of the several parts, with the exception of the clutch lever, are shown in full lines in Fig. 1 of the drawings, the normal position of said clutch lever being shown in dotted lines.

When the rod 15 is moved, either through the instrumentality of the rod 43 and the associated parts connected with the hand throttle lever, or

by the accelerator pedal 21, the actuator arm 13 of the carburetor throttle valve is moved so as to open the throttle valve to some extent before an actuation of the controlling valve member 69 is effected. This is due to the space between the portion 95 of the arm 94 and the collar 97 on said rod 15. By this arrangement fuel mixture is supplied to the intake manifold 10 of the engine in sufficient quantity for the purposes of starting the engine and letting it run idle. At the same time a vacuum is created in the cylinder 47, thereby effecting the depression of the clutch lever 52 and obviating the necessity for the driver of the car applying his foot to the clutch pedal 53 for releasing the clutch, as is the customary practice preliminary to throwing the transmission into gear for starting the car. Further movement of the rod 15, after the collar 97 has engaged the portion 95 of the arm 94, will move the rod 91 in the direction to rock the lever member 75 and thereby move the port 80 out of communication with the nipple extension 65 and into communication with the port 81. Thus, upon the acceleration in the power and speed of the engine due to the increased supply of fuel the clutch lever is released to the action of the spring 56 which throws the clutch in as the atmospheric pressure is restored to the cylinder 47. Owing to the angular set of the slotted portion 82 of the lever member 75 in which the stud 84 is slidably mounted, and due also to the friction created between the end of the valve member 69 and cap member or head 67 by the spring 79, said lever member 75 will move just sufficiently to bring the ports 80 and 81 into register as shown in Figs. 3 and 5, the stud 84 sliding towards the outer end of the slot 83 during the excess travel of the rod 91, the pivotal connection 93 between said rod and the arm 94 also permitting of this action. Obviously, therefore, the clutch lever 52 is automatically moved to and held in the clutch disengaging position as shown in full lines in Fig. 1 of the drawings when the carburetor throttle valve is partially open for the idle operation of the engine, as when starting the car or in slowing down when in traffic or under other conditions, but as soon as the throttle valve is opened to a greater extent for the propulsion of the car the clutch lever is permitted to return to engaging position, in which condition it remains during any acceleration of the engine.

In accordance with the provisions of the present invention it will be practically unnecessary, at any time, for the driver to operate the clutch by direct application of his foot to the clutch pedal lever, it merely being required of him to properly initially manipulate the hand throttle lever in starting the engine and thereafter to control the carburetor throttle valve by manipulating the accelerator pedal alone. However, while the clutch lever is automatically operable said lever may also be operated by the direct application thereto of the driver's foot in the ordinary way without interference of the mechanism which effects the automatic operation, whether said mechanism is in working order or not.

Obviously, the mechanism may be modified in many respects in its general application and in the details of structure without in the least departing from the spirit and scope of the invention as defined by the appended claims. The invention, therefore, is not limited to the specific construction and arrangement shown in the accompanying drawings.

Having thus described my invention, what I

claim as new and desire to secure by Letters Patent is:

1. In a drive control means for automobiles and the like, a device for automatically depressing the clutch pedal lever, said device comprising a cylinder having a reciprocatory piston therein, an operable connection between said piston and said clutch pedal lever, a pipe connection between said cylinder and the fuel intake manifold of the engine, a controlling valve in said pipe connection having a rotatable element provided with a port normally establishing communication through said pipe connection between said cylinder and said fuel intake manifold, said controlling valve having an external port for communicable registration with the port in its rotatable element, and means for rotating said valve element to bring said two ports into registration whereby to void said pipe connection between said controlling valve and the fuel intake manifold, said means including a lever arm having a slotted angular forward extension, an operating rod having a pivotal and slidable connection in said slotted portion of said lever arm, and a compensating lost motion connection with the operating means for the throttle valve which controls the fuel supply, whereby said controlling valve is normally set to establish communication through said pipe connection between said cylinder of the clutch actuating device and the fuel intake manifold and remains in said normal condition until the throttle valve is initially opened to a certain degree, and upon further opening of said throttle valve said controlling valve is operated to void the communicable connection with the fuel intake manifold and bring the two ports of said controlling valve into communicable registration whereby to admit atmospheric pressure to the cylinder of the clutch actuating device.
2. The herein described controlling mechanism including a power cylinder having a pipe connection with the fuel intake manifold of the engine, a controlling valve for said pipe connection comprising a cylindrical body portion having an end nipple extension and a lateral nipple extension for the pipe connection, and also provided with an exhaust port, a hollow cylindrical member rotatably fitted in said cylindrical body, said rotatable member being open at one end for communication with the end nipple extension and having a lateral opening for communication with the lateral nipple extension of said body portion, said lateral opening of said rotatable valve member being also arranged for communicable registration with the exhaust port of said cylindrical body portion, said rotatable member being closed at its end opposite to its open end and provided with an axial spindle extension projected through an opening provided therefor in
3. In a clutch control mechanism for an automotive vehicle provided with a throttle, an accelerator and a clutch pressure differential operated means for operating the clutch, valve means controlling the operation of said pressure differential operated means, and linkage interconnecting said throttle, valve and accelerator, said linkage comprising means directly interconnecting said throttle and accelerator, other means slidably mounted on said first mentioned means and directly connected with said valve, said first mentioned means being provided with spaced stops fixedly secured thereto on opposite sides of said second mentioned means whereby there is provided a lost motion connection between the accelerator and valve to effect a relative timing of the operation of the throttle and valve.
4. In a clutch control mechanism for an automotive vehicle provided with a throttle, an accelerator and a clutch, a pressure differential operated motor, valve means for controlling the operation of said motor, and linkage interconnecting said throttle, accelerator and valve, said linkage comprising means directly connecting said accelerator and throttle, means interconnecting said aforementioned connecting means and valve, including two lost motion connections, one of said latter connections being incorporated in the connection with the throttle.
5. In a clutch control mechanism for an automotive vehicle provided with a throttle, an accelerator and a clutch, a pressure differential operated motor, valve means for controlling the operation of said motor, and linkage interconnecting said throttle, accelerator and valve, said linkage comprising a plurality of links directly connecting said throttle and accelerator, a plurality of interconnected links interconnecting, with a lost motion connection, said direct connection and valve, and another lost motion connection, incorporated in said second mentioned plurality of links, at the connection between said links.

FREDRICK H. JORDAN.
